UNITED STATES PATENT OFFICE.

ROLAND F. CALHOON, OF KANSAS CITY, KANSAS, ASSIGNOR OF ONE-HALF TO
MARTHA W. LANGFORD, OF KANSAS CITY, KANSAS.

DANCING TOY.

1,391,994.

Specification of Letters Patent. Patented Sept. 27, 1921.

Application filed February 17, 1920. Serial No. 359,264.

To all whom it may concern:

Be it known that I, ROLAND F. CALHOON, a citizen of the United States, and resident of Kansas City, county of Wyandotte, State 5 of Kansas, have invented a certain new and useful Improvement in Dancing Toys, of which the following is a complete specification.

The present invention relates to toy devices, and aims to provide a novel toy construction comprising a dancing figure peculiarly mounted in such a manner as to have dancing movements imparted thereto either through the means provided for suspending 15 the figure or through the medium of the support which is provided for engagement with the feet of the dancing figure.

Accordingly, I provide a jointed dancing figure which is provided with means for suspending the same from a resilient arm, and also with a spring or resilient member which is adapted to be supported in position for engagement with the feet of the figure and in such a manner as to have vibratory movements imparted thereto for causing the figure to execute clog dancing movements upon the surface of said spring member.

It is also sought to devise a novel structure of the character described in the form 10 of a collapsible frame adapted to be folded into compact relation when not in use.

With these general objects in view, the invention will now be described by reference to the accompanying drawing illustrating a 15 suitable form of the improvement, after which the novel features therein will be particularly set forth and claimed.

In the drawing—

Figure 1 is a side elevation illustrating a 20 toy device embodying the present invention;

Fig. 2 is a plan view of the same; and

Fig. 3 is a side view illustrating the frame portion of the device in collapsed or folded relation.

Referring now to the drawing in detail, the same illustrates the present improved toy construction as comprising a jointed dancing figure 4, which is provided with a coil suspension spring 5 adapted to be 25 hooked over the free end of a resilient rod 6, the other end portion of which rod is passed through a suitable opening 7 provided in the upper end of an upright frame member 8, the adjacent end of the rod being 30 seated in a socket 9 provided in the upper 35 end of another upright frame member 10, the rod 6 being prevented from casual displacement by means of a cotter pin 11 passing through the opening 7 and an opening 12 in the rod. 60

Each of the upright members 8 and 10 is provided with a hinge member 14 for pivotally connecting said upright to the top surface of a spring or resilient board or strip 15, the arrangement being such that 65 the said members 8 and 10 are adapted to swing outwardly away from each other into folded relation with the board 15, as illustrated in Fig. 3. For supporting the said members 8 and 10 in upright relation, the 70 said members are also provided with a common form of toggle links 16 serving, when the said links are straightened as shown in Fig. 1, to firmly brace the members 8 and 10 in their upright position. For further 75 securing and latching the upper ends of the members 8 and 10 when in use, the member 8 is provided with a curved latch piece 17 connected by a hinge 18 to the upper end of said member 8, the free end of the latch 80 piece 17 being provided with a hinged hasp 19 adapted to engage over a screw eye 20 to which it is fastened by means of a suitable pin 21 as shown in Fig. 2.

In the operation of the above described 85 toy structure, the parts are arranged in opened relation as shown in Fig. 1 and one end of the resilient strip 15 (the end opposite that carrying the dancing figure 4) is rested upon a suitable support such as the 90 seat 22 of a stool or chair or the like, where it is retained in position by the person occupying said seat and operating the device. The actuation of the dancing figure 4 may then be effected by suitable vibration of the 95 rod 6, or by similar vibration of the entire frame work including the spring or resilient strip 15; this vibration may be carried out by the operator simply engaging manually the rod 6, or, where the whole frame work 100 is vibrated, by engagement of the latch piece 17 or any other portion of the collapsible frame work. In the one mode of operation, the actuation of the toy is effected through the medium of its suspension element 15, whereas in the other mode of operation the same is carried out by a joint vibration of both the suspension means and the surface of the resilient strip 15 which 105 engages the extremities of the dancing figure 110.

ure. By experience and practice, the operator may acquire a considerable degree of skill in producing the desired movements of the dancing figure and causing the same to execute a lively form of clog dance on the free end of the resilient strip 15 accompanied by appropriate swinging movements of the arms of said figure, the movements of said figure, as a whole, resulting in a very ludicrous performance.

It is thus apparent that I have devised a novel and entertaining form of device including a resilient frame structure adapted to develop all the possible movements of the dancing figure, which frame work is adapted to be collapsed into a convenient and compact form; and while I have shown what is now regarded as the preferred form of embodiment of the invention, I desire to reserve the right to make such changes as may fairly fall within the scope of the appended claims.

What I claim is:

1. A dancing toy structure comprising a jointed dancing figure and a collapsible frame work carrying a resilient rod suspending said figure, said frame work comprising a resilient strip presenting a surface in position for engagement with the feet of

the dancing figure, and a pair of spaced upright members hingedly connected with said strip and provided with means for bracing and latching said members in upright relation.

2. A dancing toy structure comprising a resilient strip, a pair of spaced upright members hingedly mounted on said strip, a curved latch piece connecting the upper ends of said member together, a resilient rod engaging and carried by said upright members, and a jointed dancing figure suspended from said rod and adapted for engagement with one end of said resilient strip.

3. A dancing toy structure comprising a resilient strip, a pair of spaced upright members hingedly mounted on said strip, a curved latch piece connecting the upper ends of said member together, a resilient rod engaging and carried by said upright members, and a jointed dancing figure suspended from said rod and adapted for engagement with one end of said resilient strip; and break joint braces connecting said upright members with said resilient strip at the outer sides of said members respectively.

In witness whereof I hereto affix my signature.

ROLAND F. CALHOON.
